United States Patent Office.

GEORGE F. GANTZ, OF NEW YORK, N. Y.

Design No. 4,075, dated May 31, 1870.

DESIGN FOR A LABEL.

The Schedule referred to in these Letters Patent and making part of the same

I, GEORGE F. GANTZ, of the city, county, and State of New York, have invented and produced a new and original Design for Labels, of which the following is a specification.

The nature of my design is fully represented in the accompanying printed illustration, to which reference is made.

The center portion of the design consists of a drinking goblet, with a spoon in it, and half of a lemon on either side.

Over the goblet is represented a lemon-squeezer, grasped by hands, and operating on the cut portion of a lemon, with the juice therefrom trickling into the glass.

Running horizontally across this center portion of the design are two straight portions of a band, on the upper of which are the words "Geo. F. Gantz & Co's," and on the lower of which are the words "Sicily Lemon Sugar." At top is a Maltese cross.

The design is surrounded by an ornamental border, the configuration of which is fully represented.

I claim as my invention—
The design for a label, as shown.

GEO. F. GANTZ.
